CLAIM

I claim the ornamental design for a heavy-duty support bracket for supporting an off-shelf merchandising display assembly, as shown and described.

DESCRIPTION

FIG. 1 is a perspective view of the support bracket according to a preferred variant of the present design;

FIG. 2 is a top view of the present design according to the preferred variant;

FIG. 3 is a right side view of the present design according to the preferred variant, with a corresponding left side view being a mirror image thereof;

FIG. 4 is a bottom view of the present design according to the preferred variant;

FIG. 5 is a front view of the present design according to the preferred variant; and,

FIG. 6 is a rear view of the present design according to the preferred variant.
